ROTARY PRINTING PRESS

Charles Alonzo Harless, Oak Park, Ill., assignor
to The Goss Printing Press Company, Chicago,
Ill., a corporation of Illinois

Application October 17, 1942, Serial No. 462,352

6 Claims. (Cl. 101—227)

The present invention relates to new and useful improvements in web-fed rotary printing presses and more particularly to an improved web guide controlling the side-lay of the web.

Objects and advantages of the invention will be set forth in part hereinafter and in part will be obvious herefrom; or may be learned by practice with the invention, the same being realized and attained by means of the instrumentalities and combinations pointed out in the appended claims.

The invention consists in the novel constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a diagrammatic view showing a printing press including the web guide of the present invention;

Figure 2 is a diagrammatic top plan view of a portion of the printing press showing the run of web;

Figure 3 is a fragmentary side elevation showing one end of the illustrative web guide of the present invention;

Figure 4 is a fragmentary plan view of the parts shown in Figure 3;

Figure 5 is a fragmentary side elevation of the other end of the web guide;

Figure 6 is a fragmentary end elevation of the parts shown in Figure 5;

Figure 7 is a diagrammatic view showing the relation of the guide rollers and web when the ends of the guide rollers are displaced horizontally to shift the web;

Figure 8 is a similar view but showing the guide rollers shifted in a horizontal direction to vary the side-lay of the web; and,

Figure 9 is a diagrammatic view showing the modified form of the present invention.

The present invention has for its object the provision of a novel and improved rotary web-fed printing press in which the printing and slitting operations can be registered with a high degree of accuracy. A further object is the provision of an improved web guide for controlling the side-lay of the web between the drier and slitting means. Still another object is the provision of an improved web guide for controlling the side register of a fast moving web of paper as it is fed through a printing press.

In accordance with the present invention there

is provided a web guiding means which illustratively comprises a pair of guide rollers mounted in side frames at their ends, one above the other and their axes staggered so that one edge of one roller is vertically aligned with the other roller. The rollers, at one end, are mounted for free rotation by means of self aligning ball bearings in a fixed frame member and are mounted at their other end in self aligning ball bearings which are carried by a frame having motion in a plane and direction normal to the run of the web, and preferably having compound motion in that plane, so that with a horizontal run of web, the one end of the rollers may be moved vertically or horizontally, while keeping the movable frame at the same distance from the fixed frame. The movement of the roller ends is preferably effected by means which permit minute, accurate variable positioning of the roller ends so that the side-lay of the web may be accurately controlled.

The guide rollers are preferably positioned to act on a printed and dried web as it is fed to slitting means, and for this purpose there is provided a rotary printing couple, which may be a multicolor printing unit, and a drier to dry the printed impression on the web before the web is slit into various ribbons preparatory to being associated, cut and, if desired, folded. The paper often is irregular and does not run true, and is even more irregular after drying so that it has heretofore been difficult to slit the web into ribbons keeping the slit lines accurately in register with the printing on one or both sides of the web. The web guide of the present invention, however, enables the web to be guided and accurately adjusted for side-lay between the drier and slitting means.

It will be understood that the foregoing general description and the following detailed description as well are exemplary and explanatory of the invention but are not restrictive thereof.

Referring now in detail to the illustrative embodiment of the invention as shown in the accompanying drawings, there is provided a multicolor rotary web-fed perfecting printing unit, of which only the second impression cylinder 10 and the two color printing cylinders 11 and 12 are shown. The perfected web 13 is dried by passing through the drier 15 where it is subjected to heat and circulating air to dry the ink. The drier may be of any convenient and desired form but is shown as comprising a gas heated oven like apparatus through which the web passes adjacent the gas burners 16. The web then passes to the cooling rollers 17 and 18 which cool the web

after which the web is led over side registering roller 20 and under side registering roller 21 prior to being passed to the slitting rollers 24 which slit the web 13 as they bear against roller 25 to form the ribbon 26.

Thereafter the web ribbons 26 are associated, cut and folded as desired by conventional means.

Means are also provided for minutely and accurately variably positioning one end of each of the rollers 20 and 21 while maintaining the rollers parallel to each other and by these means the rollers may be moved at one end up or down and forward or back to vary their angular relation to the running web. Preferably, the rollers are moved in a vertical direction with respect to the horizontal web being fed to the roller 20 and from the roller 21, as this produces a greater side movement of the web than does the horizontal movement of the rollers, although the rollers may be moved in both directions while maintaining their ends in the original plane.

On one of the side frames 30 of the press is fixed a bracket 31 on which are mounted bearing seats 32 and 33 in each of which is mounted a self aligning ball bearing 34 by which the end of the rollers 20 and 21 are rotatably mounted and supported. The bearings 34 are so located relatively to the side of the rollers lie on opposite sides of a vertical plane and are both tangent thereto thereby providing a vertical run for the web as it passes from roller 20 to 21.

At the other end of the rollers, they are rotatably mounted and supported by means of self aligning ball bearings in bearing seats 37, 38 which are mounted on the other side frame 39 of the press and may be minutely and accurately variably positioned by movement in a plane which is vertical, or normal to the web. For this purpose there is provided a bracket 40 having upper and lower members 42, 43 extending horizontally from the vertical base member 44 and supporting the vertically extending parallel guide rods 45. Journalled in the upper and lower members 42, 43 is a threaded shaft 47 having a hand wheel 48 at its upper end and a thrust collar 49 at its lower end, rod 47 extending parallel to the guide rods 45 and preferably being positioned between them. A yoke-like frame 50 is mounted for vertical movement on the guide rods 45 and this yoke-like frame has laterally extending lugs 52 near its top and bottom which are provided with alined bores to fit the guide rods 45, thereby holding the yoke-like frame 50 against any but vertical movement. At the upper part of the frame 50 is formed a pair of inwardly extending brackets 54, and a similar pair of inwardly extending brackets 55 are provided at the lower portion of the frame 50. Each pair of brackets supports a pair of guide rods 56, all of the guide rods 56 extending parallel to each other and at right angles to the guide rods 45. The bearing seat 37 for the upper roller 20 is provided with a pair of bores by which it is slidably mounted on the upper pair of guide rods 56, while the lower bearing seat 38 is similarly mounted on the lower pair of guide rods 56 thus providing for the horizontal movement of the rollers 20 and 21.

Means are also provided for minutely and accurately variably positioning the rollers by movement of one of their ends in horizontal direction, and for this purpose a threaded rod 60 is journalled in the upper brackets 54 and a similar threaded rod 61 is journalled in the lower brackets 55, the rods 60 and 61 extending parallel to their adjacent guide rods 56. These guide rods

pass through correspondingly threaded apertures in the bearing seats 37, 38 so that rotation of the threaded rods minutely moves the roller end in a horizontal direction.

5 Rod 60 is held against axial movement by means of the hand wheel 64 at one end and bevelled gears 65 at its other end, while the rod 61 is held against axial movement by thrust roller 66 and bevelled gear 67, and rods 60 and 61 are connected together for movement in unison by means of the bevelled gears 68, 69 mounted on shaft 70 which is journalled in the brackets 71 also formed integrally with the yoke frame 50.

10 Thus by rotation of the hand wheel 64, the threaded rods 60 and 61 are similarly moved an equal amount to move the end of rollers 20 and 21 in a horizontal direction while maintaining the rollers parallel to each other at all times. Hand wheel 48 serves to raise and lower the rollers, and may be operated independently of the hand wheel 64.

15 As shown in Figure 2 the web 13 is shown as it is fed to the roller 20, the dot-dash lines indicating the feed of web to the roller 20 when it is being fed in a distorted condition requiring correction of its run by the guide rollers 20 and 21 so that the printing and slitting will be properly registered. The dot-dash lines may also be considered as representing the run of a true web as its side-lay is being varied for proper registration of the web at the slitters.

20 As shown in Figure 7, the movable end of rollers 20 and 21 has been raised so as to position the rollers at an angle with reference to normal run of web. As illustratively shown in this figure raising of the near ends of the rollers 20 and 21 has positioned the guide rollers so that the web will be shifted toward the near end of the rollers as it passes over it. Figure 8 shows the variable positioning of the rollers 20 and 21 by movement of their near ends to the left and in a horizontal direction, thereby effecting a shifting of the web toward the far ends of the rollers as the web passes over them.

25 Figure 9 shows an alternative and modified embodiment of the invention in diagrammatic form. As there shown the rollers 20 and 21 are individually mounted in anti-friction bearings which hold one end of each roller fixed and provide for the relative movement of the other end of each roller. However as shown in this figure roller 20 is rotatably mounted in a fixed position at one end while roller 21 is rotatably mounted in a fixed position at its other end, and means are also provided for simultaneously variably positioning the movable end of each roller while maintaining the rollers parallel to each other.

30 As shown in detail, the roller 20 is rotatably mounted by its shaft 71 in a fixed bearing support 72, while the other end of its shaft 71 is rotatably mounted in a movable bearing support by a threaded shaft 74 journalled in a bracket 75 secured to the side frame of the press. 35 Roller 21 is likewise mounted by its shaft 76 in a bearing support 77 which is fixed, and at its other end is mounted in a bearing support 78 carried on and supported by the threaded shaft 79 which is rotatably journalled in the bracket 80. A hand wheel 81 on shaft 82 serves to turn the bevelled gears 83 and 84 meshing with bevelled gears 85 and 86 respectively, gears 85 and 86 being fixed to the threaded shafts 79 and 74 respectively. Thus as hand wheel 81 is turned 40 the movable bearing supports 73 and 78 are

simultaneously moved in opposite directions to the same extent thereby maintaining the rollers 20 and 21 parallel to each other as they are variably positioned. In use the web is led over roller 20 and under roller 21 in the same manner as shown in Figures 7 and 8.

The invention in its broader aspects is not limited to the specific mechanisms shown and described but departures may be made therefrom within the scope of the accompanying claims without departing from the principles of the invention and without sacrificing its chief advantages.

What I claim is:

1. In a web guiding means, the combination of a pair of guide rollers, a pair of relatively movable frame members, one of which is movable normal to the axes of the rollers, means for mounting the rollers in said frame members for rotation about parallel axes and means for minutely variably positioning the movable frame members in directions parallel with the run of the web passing to and from the rollers.

2. In a web guiding means, the combination of a pair of parallel guide rollers, a pair of parallel frame members, one frame member being movable with reference to the other in its own plane, self alining ball bearings by which the rollers are journalled in the frame members, and means for minutely variably positioning the slideable frame member in directions normal to and parallel with the run of web to and from the rollers.

3. In a web guiding means, the combination of a pair of parallel guide rollers, a pair of parallel frame members, one frame member being movable with reference to the other in its own plane, self alining ball bearings by which the rollers

are journalled in the frame members, and means for minutely variably positioning the slideable frame member in directions parallel with the run of web to and from the rollers.

5 4. In a web guiding means, the combination of a pair of parallel guide rollers, a pair of parallel frame members, one frame member being movable with reference to the other in its own plane, self alining ball bearings by which the rollers are journalled in the frame members, and means for minutely variably positioning the slideable frame member in directions normal to the run of web to and from the rollers.

10 5. In a rotary web printing press having a printing couple, a drier, slitting means and means for guiding the web through the couple, driers, and slitting means, the combination of a pair of parallel guide rollers over which the web passes and means for shifting the rollers to change their angle with respect to the normal run of web, whereby irregularities in the dried web may be compensated for and the side-lay of the web maintained at the slitting means.

20 6. In a rotary web printing press having a printing couple, a drier, slitting means and means for guiding the web through the couple, driers, and slitting means, the combination of a pair of parallel guide rollers over which the web passes and means for shifting the rollers at one end in a direction normal to the run of web to and from the guide rollers to change their angle with respect to the normal run of web, whereby irregularities in the web may be compensated for and the side-lay of the web maintained at the slitting means.

25 30 35 CHARLES ALONZO HARLESS.
